UNITED STATES PATENT OFFICE.

JULIUS P. ANDERSON, OF DES MOINES, IOWA, ASSIGNOR OF ONE-HALF TO HENRY LAGERQUIST, OF DES MOINES, IOWA.

SURFACING MACHINE.

1,469,512.

Specification of Letters Patent. Patented Mar. 14, 1922.

Application filed March 8, 1921. Serial No. 450,701.

To all whom it may concern:

Be it known that I, JULIUS P. ANDERSON, a citizen of the United States, and a resident of Des Moines, in the county of Polk and 5 State of Iowa, have invented a certain new and useful Surfacing Machine, of which the following is a specification.

This invention relates to improvements in machines for surfacing floors and the like. 10 Heretofore a large amount of the surfacing of newly laid floors has been done by the hand scraper and sand paper blocks which are also operated by hand. This is an expensive operation which requires considerable time and one in which it is somewhat difficult to obtain a floor with a smooth surface free from irregularities.

It is the object of my invention to provide a mechanically operated device of simple, 20 durable and inexpensive construction for surfacing newly laid floors, and so arranged that a comparatively smooth surface may be easily and quickly obtained.

A further object is to provide a mechanically operated device for surfacing floors having a motor or similar device for operating the surfacing mechanism.

A further object is to provide a power driven mechanically operated mechanism for 30 surfacing floors provided with means whereby any one of a number of different kinds of cutting or finishing devices may be easily and quickly attached to or removed from the mechanism.

A further object is to provide a power driven mechanically operated floor surfacing device employing a plurality of endless cutting or surfacing members designed to operate in opposite directions so as to counter- 40 act their tractive effect or their tendency to advance the machine over the floor surface.

A still further object is to provide in a power driven floor surfacing mechanism adapted to receive any one of a series of different kinds of surfacing devices, means for changing the relative speed between the motor and the mechanism for operating the surfacing device.

A still further object is to provide in a power driven mechanism employing a plurality of parallel and adjacent endless cutting or surfacing devices, improved means for driving said endless cutters or surfacers.

These and other objects will be apparent 55 to those skilled in the art.

My invention consists in the construction, arrangement and combination of the various parts of the device, whereby the objects contemplated are attained, as hereinafter more fully set forth, pointed out in my claims, 60 and illustrated in the accompanying drawings, in which:

Figure 1 is a side elevation of my improved floor surfacing machine showing a portion of the gear casing broken away and 65 also a portion of the front side.

Figure 2 is a transverse sectional view taken on the line 2—2 of Figure 1.

Figure 3 is a plan view taken on the line 70 3—3 of Figure 2.

Figure 4 is a detail side elevation of the speed reducing and changing mechanism for controlling the surfacing devices.

Figure 5 is a detail side elevation of a fragmental portion of my improved machine 75 showing a certain modification and also the manner in which the continuous scraper is applied.

Figure 6 is one of the detachable shoes for holding the surfacing devices adjacent to 80 the floor.

Figure 7 is an end elevation of one of the scrapers and the mechanism for detachably mounting the same.

Figure 8 is a front elevation of Figure 7. 85

Figure 9 is a side elevation of my complete surfacing device.

My improved surfacing machine comprises a supporting member 10 which may be formed of wood or metal, and having 90 recesses 11 at its forward end and a transversely arranged shaft 12 on the lower member of said recess.

This member 10 is supported at the central portion of said shaft 12 so that each 95 of the ends of said shaft may be designed to receive a roller 13. Each end of said rollers is provided with recesses 14 in which are mounted roller bearing members having a sleeve 15 designed to firmly engage the 100 said shaft 12. Said sleeve is provided with a suitable ball race designed to carry balls 16 which are designed to run in a sleeve 17, the said sleeve 17 being mounted in each end of the rollers 13, as clearly shown in 105 Figure 3.

For securing the rollers to the shaft, I have provided a washer 18 designed to enter the recesses 14, said washer being held in position by means of a nut 19. The washer 110

- 18 is of a diameter substantially equal to the diameter of the recesses 14 and is designed to have its inner face engage packing members 20 which are mounted in annular 5 grooves in the bottom of the recesses 14. This packing member may be formed of felt or any other suitable material, and is for the purpose of preventing dust or dirt from entering the bearing members.
- 10 The inner one of each of the recesses 14 is provided with a beveled gear 21 which is designed to rest against the ends of the bearing members and also designed to engage the packings 20, and fixed to the rollers 13 by means of pins 22.
- 15 These beveled gears 21 are set in the recesses 14 in such a manner that they enter into the rollers 13 and the upper edge substantially against the member 10. This permits 20 the inner ends of the rollers 13 to operate as near together as possible for reasons hereinafter to be made clear.
- 20 The forward end of the member 10 is provided with a half boxing 23 mounted above 25 the recesses 11, which is designed to carry a semi-boxing member 24. These boxings are held in position relative to each other and to the member 10 by means of bolts 25. The said boxing is designed to carry a vertical 30 shaft 26 having its lower end provided with a beveled gear 27 which is designed to mesh with the upper edges of the beveled gears 21 in such a manner that the said beveled gears are operated in opposite directions, 35 which will in turn cause the rollers 13 to be operated in opposite directions as the shaft 26 is rotated. The edges of the beveled gear 27 enter the recesses 14, as clearly shown in Figure 2. The boxing members 23 and 24 40 are designed to receive a thrust bearing 28 and a ball bearing 29 which are shown in section in Figure 2.
- 45 Secured to the top edge of the member 10, I have provided a cover plate 29^a which extends the entire length of the said member 10, and is provided with downwardly extending side portions 30. The forward end of the plate 29^a is provided with a casing 31 upon which is mounted a motor 32 of the 50 vertical type, having an extended shaft 33, the lower end of which is provided with squared portions 34 which extend downward through the top of the casing 31 at a position behind the upper end of the shaft 26.
- 55 A sleeve 35 is slidably mounted on the portion 34 which is designed to carry pinions 36 and 37. A groove 38 is formed between the pinions 36 and 37 which is designed for the purpose of receiving inwardly extending 60 ends 39 of a fork 40 which is pivotally secured to an upright 41, as clearly shown in Figure 4. The fork 40 is provided with a handle 42 which is designed to extend through a slot 43 in one side of the casing 65 31. The said slot is provided with adjacent pivoted pawl 44 which is provided with notches in its edge and is for the purpose of holding the lever 42 in either of its positions of movement.
- 70 By this arrangement the sleeve 35 may be elevated or lowered on the shaft 26 as desired. The shaft 26 is provided with a gear 45 designed to engage the gear 36 when the sleeve 35 is in its lower position of movement. The said shaft 26 is also provided with a gear 46 75 designed to engage the gear 37 when the sleeve 35 is in its upper position of movement. The gear 46 is of a greater diameter than the gear 35 and the gear 36 is of a greater diameter than the gear 37, so that 80 when the gear 36 is in mesh with the gear 45, the shaft 26 will be rotated at a higher rate of speed than when the gear 37 is in mesh with the gear 46, thereby providing means whereby the speed of the rollers 13 85 may be run at a different speed relative to the speed of the motor 32 which is preferably of the uniform speed type.
- 90 The motor 32 may be provided with a regular motor controlling device such as a switch, and may be stopped by operating a switch which also serves to throw the mechanism into and out of operation.
- 95 The back portion of the member 10 is provided with a slot 47 and also a slidably mounted yoke 48 which is designed to operate in grooves 49. This yoke 48 is provided with set screws 50, the inner end of which is designed to engage the end of the member 10 so the said yoke may be adjusted 100 for the purpose of tightening the belts or surfacers, as will hereinafter be made clear.
- 105 Each of the members of the yoke 48 is provided with a hub 51, into which a shaft 52 is mounted, which also extends through the slot 47. The hub 51 is designed to receive a sleeve 53 similar to the sleeve 15, the sleeve 53 being designed to carry a corresponding ball bearing 54. Ball bearings similar to those on the shaft 12 are provided for the 110 outer end of the shaft 52. Each set of the said ball bearings is designed to carry a roller 55 similar to the rollers 13, and is of the same diameter, the only difference being the rollers 55 are not provided with the inner recesses 14.
- 115 Secured in the bottom edge of the member 10, I have provided a series of transversely arranged shafts 56, each of which is provided with a washer 57 and a nut 58 similar 120 to those on the shaft 12. Each of the shafts 56 is designed to receive a roller 59 which is of considerably smaller diameter than the rollers 13 or 55, but are arranged so that their lower faces are in line with the lower 125 faces of the end rollers.
- 130 These rollers are designed to receive belts 60 which are continuous and may have their outer surfaces provided with an abrasive substance such as sand paper.

By the construction disclosed, it will be seen that a belt may be placed on each set of rollers which will be driven in opposite directions as the motor is operated.

5 For protecting the bearings of the rollers against dirt to a certain extent, I have provided a downwardly hanging side plate 61 for each of the members 30 which is mounted by means of hinges 62 so that the belts 10 may be placed in position or moved at the will of the operator by merely raising the side members 61 and placing the belt over the rollers edgeways. I have also provided downwardly extending portions 63 for the 15 forward end of the plate 29. Secured to the back end of the top of the plate 29, I have provided a handle 64 which is for the purpose of assisting in operating the device.

Projecting laterally from the side of the 20 members 30, I have provided pins 66 upon which is pivotally mounted a yoke 67 secured to the lower end of a handle 68. This yoke 67 is formed of spring material in such a manner that its members may be separated 25 to permit them to be free from the pins 66 when it is desired to remove the said handle.

In order to obtain the proper tension of the belts and take up any slack which may be produced by one of the belts stretching a 30 little more than the other, I have provided a pin 69 extending laterally from each side of the member 10, each of said pins being provided with a bell crank arm 70 having its upper end provided with a shaft 71, each 35 end of which is provided with a roller 72, as clearly shown in Figures 3 and 5. The lower end of the bell crank 70 is provided with a spring 73 which has one end mounted in a pin 74. The belts 60 may have their outer 40 faces provided with any desired grade of an abrasive or they may be provided with a buffed surface for polishing.

The practical operation of my device is substantially as follows:

45 When it is desired to polish a waxed floor, I loosen the set screw 50 and move the yoke 48 inward in its grooves 49, thereby permitting the rollers 55 to be moved closer to the rollers 13, after which I grasp a suitable 50 polishing belt which may be formed of any suitable polishing material, and elevate one of the doors 61 and place the said belt over the rollers 13 and 55, having the lower run of the belt under the rollers 59. The opposite 55 belt is placed in the same manner, after which the set screw 50 is operated and the yoke 48 moved outward, causing the rollers 55 to engage the belts and the said belts tightened any desired amount.

60 The surfacing machine is then placed on the floor to be polished with the lower run of the belt resting on the floor. I then move the lever 42 so that the gear 36 is in mesh with the gear 45, after which the motor is

started and the belts will be operated in reverse directions. 65

On account of the said belts being operated in a reverse direction, the device has a slight tendency to twist or rotate about a vertical axis, but its longitudinal movement 70 in either direction is neutralized by the fact that the belts are run in opposite directions. The twisting movement, however, is easily taken care of by means of the handle 68. In this connection, this is the reason why I 75 have mounted the beveled gears 21 in the recesses 14 in the manner that I have, so that the inner edges of the belts may run as close to each other as possible and thereby eliminate as near as possible the twisting 80 tendency which would increase as the belts are separated from each other.

If it is desired to sand paper a floor, I remove the polishing belts by first loosening the yoke 48 after which the belts are free to 85 be removed, and place on the said rollers a sanding belt.

When it is desired to scrape a floor, which is usually the first operation in finishing a new floor, I have provided a belt 75 similar 90 to the one shown in Figure 5, provided with a series of transverse plates 76 which are connected to the outer surface of the belts at their forward edges by means of rivets 77. Each of these plates 76 is provided with a laterally extending portion 78 having a groove 79. This groove 79 is designed to receive a scraper blade 80 secured in position by means of bolts 81. The blades 80 are given the proper angle for the 95 most efficient work, which is substantially as shown in Figure 5, the said belt being designed to rotate in a clockwise direction. 100

When the belt 75 has been placed in position, I usually remove the rollers 59 and 105 substitute them with a block or the shoe 82, which is provided with holes 83 to receive the shaft 56, the said holes being provided with enlarged portions 84 for the purpose of receiving the nuts 58. This shoe is of such 110 width that its under face will be in line with the under faces of the rollers 13 and 55. Each of the shoes is provided with a concave portion 85 to fit the contour of the adjacent rollers. 115

When the belt 75 has been placed in position, the motor may be operated and the lever 42 may be shifted to its reverse position of movement, which will cause the gear 37 to engage the gear 46 and the speed of 120 the rollers 13 to be reduced as it is not desirable to operate the scraper at as high speed as the polishing belts, for the reason that the scrapers require considerable more power for their operation.

It will be observed that as the scraper engages the floor surface, it will have a tendency to move backward which is taken 125

care of by means of the plate 76 engaging the belt 75. This is one reason for substituting the shoe 82 for the rollers, as the lower surface of the shoe presents an even and continuous surface under which the plate 76 may operate freely so the said blades may operate without vibration as they are moved over the surface of the floor.

10 By this arrangement, it will be seen that as the scrapers are operated, the high places of the floor will be engaged by the scrapers first, which will produce an even surface to a floor which can not be produced by a 15 single hand operated scraper. The shoes 82 may also be used with the sand or polishing belt if so desired.

Thus it will be seen that I have provided a surfacing machine which is power driven, 20 and which is adapted to produce a very even surface due to the length of the engaging surface of the belt. The surfacing machine may be easily and quickly moved from one position to another on the floor 25 surface.

I claim as my invention:

1. In a floor surfacing device, a supporting member having at each end a set of laterally extending shafts, a roller for each 30 of said shafts, a surfacing belt for each corresponding set of shafts, the lower runs of said belts being designed to engage a floor surface, means mounted on said support for driving said belts in opposite directions, 35 said support being so arranged that the entire weight thereof and the driving means are carried by the lower runs of said belts.

2. In a floor surfacing device, a comparatively thin supporting member, each end of 40 which is provided with a set of laterally extending and aligned shafts, each of said shafts being provided with a roller, a surfacing belt for each set of corresponding rollers, said belts being designed to have 45 their lower runs engage the floor surface, means for adjustably mounting the shafts at one end of said support to tighten and loosen said belts, and means actuating said adjusting means, means for driving said belts in opposite directions, the entire weight 50 of said support and said driving means being designed to be carried by the lower runs of said belts.

3. In a floor surfacing device, a supporting member having at each end a set of laterally extending and aligned shafts, a roller for each of said shafts, a surfacing belt for each corresponding set of shafts, the lower runs of said belts being designed 60 to engage the floor surface, means mounted on said support for driving said belts in opposite directions, said support being so arranged that the entire weight thereof and the driving means are carried by the lower 65 runs of said belts, and of a length sub-

stantially equal to the length of said belts and of a width substantially equal to the combined width of both of said belts.

4. In a floor surfacing device, a supporting member having at each end a set of laterally extending and aligned shafts, a roller for each of said shafts, a surfacing belt for each corresponding set of shafts, the lower runs of said belts being designed 70 to engage a floor surface, said support including means for engaging the upper face of said lower runs to hold them in alinement with the under faces of said rollers, means mounted on said support for driving said belts in opposite directions, said support being so arranged that the entire weight thereof and the driving means are carried by the lower runs of said belts.

5. In a floor surfacing device, a support, adjacent surfacing belts rotatively mounted 85 in said support in a common plane adjacent and parallel to each other, the lower runs of said belts being designed to engage a floor surface, means mounted on said support for driving said belts in opposite directions, said support being so arranged 90 that the entire weight thereof and the driving means are carried by the lower runs of said belts.

6. In a floor surfacing device, a support, 95 adjacent surfacing belts rotatively mounted in said support in a common plane and parallel to each other, means for rotating said belts simultaneously and in opposite directions, means for simultaneously adjusting the tension of said belts, and an independent and yielding tension device for 100 each of said belts.

7. In a floor surfacing device, a support, 105 a pair of adjacent and aligned rollers fixed to and rotatively mounted at one end of said support, a second pair of adjacent and aligned rollers adjustably mounted at the opposite end of said support parallel with and in line with the first said pair of rollers, a 110 surfacing belt for the corresponding rollers of said pairs, the lower runs of said belts being designed to engage the floor surface, means for adjusting the second pair of rollers to increase or decrease tension, and independent and yielding tension device for 115 each of said belts, means for driving said belts simultaneously and in opposite directions, the weight of said supporting means and the said driving means being carried by the lower runs of said belts, the length of said supports being substantially equal to the length of said belts and of a width substantially equal to the combined width of said belts.

8. In a floor surfacing device, a supporting member having at each end a set of laterally extending and aligned shafts, a roller for each of said shafts, a surfacing belt for each corresponding set of shafts, the 120 125 130

lower runs of said belts being designed to engage a floor surface, means mounted on said support for driving said belts in opposite directions, a motor on said support and means actuated by said motor for driving said belt driving means at variable speeds relative to the speed of said motor, said support being so arranged that the entire weight thereof and the driving means 10 are carried by the lower runs of said belts.

9. In a floor surfacing device, a support, a horizontal shaft fixed in said support having laterally extending ends, a roller rotatively mounted on each of said ends, each 15 of said rollers having its inner end provided with a recess, a beveled gear in each of said recesses fixed to the bottom thereof, a beveled gear communicating with both of said beveled gears, a vertical shaft for the 20 last said beveled gear rotatively mounted in said support, spaced gears fixed to said vertical shaft, said gears being of different diameters, a motor fixed to said support having an extended shaft parallel to said vertical shaft, a sleeve provided with pinions of different diameters slidably mounted on said 25 extended shaft, means for shifting said sleeve to cause either of said pinions to engage a corresponding one of said spaced gears for operating said rollers at variable speeds, a second horizontal shaft adjustably mounted in said support and having laterally extending ends, a roller rotatively mounted on each of said ends, a surfacing belt for each set of corresponding rollers, 30 means for adjusting the last said shaft for tightening or loosening said belts, the lower runs of said belts being designed to rest on the surface to be finished, a cover plate for said support having a downwardly extending portion at one end and downwardly 35 extending side portions terminating at a point above the top runs of said belts, a hinged door depending from the lower edge of each of the side members, a pivoted and detachable handle for said support.

10. In a floor surfacing device, a support, a horizontal shaft fixed in said support having laterally extending ends, a roller rotatively mounted on each of said ends, each 40 of said rollers having its inner end pro-

vided with a recess, a beveled gear in each 45 of said recesses fixed to the bottom thereof, a beveled gear communicating with both of said beveled gears, a vertical shaft for the last said beveled gear rotatively mounted in said support, spaced gears fixed to said vertical shaft, said gears being of different diameters, a motor fixed to said support having an extended shaft parallel to said vertical shaft, a sleeve provided with pinions of different diameters slidably mounted on said 50 extended shaft, means for shifting said sleeve to cause either of said pinions to engage a corresponding one of said spaced gears for operating said rollers at variable speeds, a second horizontal shaft adjustably 55 mounted in said support and having laterally extending ends, a roller rotatively mounted on each of said ends, a surfacing belt for each set of corresponding rollers, 60 means for adjusting the last said shaft for tightening or loosening said belts, the lower runs of said belts being designed to rest on the surface to be finished, a cover plate for said support having a downwardly extending portion at one end and downwardly 65 extending side portions terminating at a point above the top runs of said belts, a hinged door depending from the lower edge of each of the side members, a pivoted and detachable handle for said support.

11. A surfacing member for mechanically operated surfacing machines comprising an endless belt having a series of transversely arranged plates, each of said plates being secured to its outer surface by means of rivets through the forward edge of said plate, each of said plates being provided with an angularly and laterally extending flange, a scraper blade for each of said flanges and means for detachably securing said blade 80 to said flange.

Des Moines, Iowa, February 25, 1921.

JULIUS P. ANDERSON.
